UNITED STATES PATENT OFFICE

STANLEY A. JACQUES, OF CHICAGO, ILLINOIS, ASSIGNOR TO INTERNATIONAL COMBUSTION ENGINEERING CORPORATION, OF NEW YORK, N. Y., A CORPORATION OF DELAWARE

POWDERED-FUEL-BURNING BOILER FURNACE

Application filed August 24, 1926. Serial No. 131,149.

This invention relates to boiler furnaces, and particularly to those in which the fuel to be burned is in powdered form, as, for example, pulverized coal. Stated in another way, the invention is particularly useful in connection with pulverized fuel burning furnaces in which the combustion chamber is largely defined by tubular water walls.

One of the primary objects of the invention is to provide, in a furnace of the character described, substantial uniformity of circulation conditions throughout.

More specifically, it is an object of the invention to provide the novel assemblage and combination of parts hereinafter described.

How the foregoing, together with such other objects and advantages as may herein-after appear, or are incident to my invention, are realized, is illustrated in preferred form in the accompanying drawings, wherein—

Fig. 1 is a vertical section through a powdered fuel burning furnace illustrating my improvements, with certain of the parts appearing in elevation;

Fig. 1^a is a fragmentary side elevation illustrating certain headers and connection tubes of Fig. 1 in full view;

Fig. 2 is a fragmentary plan section taken substantially on the line 2—2 of Fig. 1;

Fig. 3 is a fragmentary sectional elevation of a modification of the invention; and

Fig. 4 is a fragmentary plan section of Fig. 3.

Referring to Fig. 1, the reference character A denotes the combustion space or chamber of the boiler furnace, which chamber is largely defined by evaporating elements or water walls. Powdered fuel and air may be admitted to the combustion chamber in a downward direction through one or more burners 1 located in the roof 2. Air, in addition to that admitted with the fuel, may be admitted through a number of damper-controlled intakes 3 in the front wall 4. The two side walls of the combustion chamber are provided with water walls B composed of a plurality of vertically extending tubes, and the rear wall is provided with a similar water wall C. The tubes of these walls are prefer-

ably provided with fins which cooperate with the tubes to constitute the evaporating walls. A water screen D defines the lower portion of the combustion space of the furnace, which screen is composed of a plurality of tubes spaced sufficiently apart to allow the refuse precipitating out of the fuel and flame stream to pass through the screen.

The water walls are provided with appropriate headers, and it will be seen that the tubes of the side walls B connect, at their lower ends, into a header 5, and at their upper ends into the headers 6 and 7. In the embodiment shown, it is pointed out that certain of the tubes of the side walls B are shorter than others, the longer tubes 8 being connected at their upper ends of the header 6 and the shorter tubes 9 to the header 7. These headers 6 and 7 are connected in circulation by means of the connecting tubes 10. By this arrangement of the tubes of the side walls, protection is afforded for the throat of the combustion chamber.

The tubes 11 of the rear wall C connect at their upper ends into the upper headers 12, and at their lower ends into the junction blocks or boxes 13, and the tubes 14 of the water screen D connect at one end into the header 15, and at the other end into the junction blocks 13, which are common to the water screen and the rear wall.

The headers above referred to are preferably located on the outside of the furnace, and the tubes connecting them pass through the furnace walls, the tubes of the side and rear walls being suitably bent for connection to their headers.

A relatively light sheathing 16 is associated with the tubular walls, and an ash pit 17 is provided beneath the water screen D for receiving the refuse.

A plurality of pipes 18 are provided on the outside of the furnace for connecting the lower headers of the side walls with the upper headers thereof. Thus, a certain measure of local circulation is afforded which tends to insure continuity of circulation through the water wall tubes.

In the present instance, a substantially horizontal tubular boiler E is arranged above

the throat of the furnace, the tubes thereof inclining slightly forwardly and upwardly, which boiler is heated by the products of combustion leaving the chamber A.

5 The tubular water walls and the water screen are connected into the circulation of the boiler as follows: Downflow pipes 19, outside the chamber A, connect the lower side wall headers 5 and the front water screen header 15 to the rear header 20 of the boiler E, and upcomer tubes 21 connect the upper header 12 of the rear wall C to the front header 22 of the boiler E. Upcomer tubes 23 are also provided for connecting the upper headers 6 of the side walls to the front header 22 of the boiler.

10 In this connection, it is pointed out that the upcomer tubes are so arranged as to constitute a row of the tubes of the tubular boiler, as clearly illustrated in Figs. 1 and 2, which improves the circulation, and also maintains uniformity of circulation throughout all of the water walls. The upcomer tubes leading from the rear wall extend upwardly 15 from the header 12 and then longitudinally of the boiler, and the upcomer tubes leading from the side walls extend inwardly from the headers 6 and then longitudinally of the boiler, so that a row of substantially horizontal upcomer tubes is provided passing across the throat of the combustion chamber.

15 In the modification illustrated in Figs. 3 and 4, the upcomers are carried up between certain rows of the tubes of the tubular boiler, so that they constitute an upper row of said tubes.

20 The advantages of the arrangements herein set forth will be fully understood by those skilled in the art.

25 Referring to the arrangement of Fig. 1, it will be seen that the top, bottom, sides, and rear of the combustion space are defined by tubes subject to radiant heat, and that there is circulation in one direction through all of such tubes, the various water tubes being connected in the same general fashion to the boiler, whereby substantially uniform conditions maintain throughout.

30 I claim:—

35 1. In combination with a substantially horizontal tubular boiler, a combustion chamber therebelow having side water walls including appropriate headers, upcomers for said water walls connected into the circulation of the boiler and constituting a portion of a row of the tubes of the tubular boiler, and means for introducing fuel to be burned in said combustion chamber.

40 2. In combination with a substantially horizontal tubular boiler, a combustion chamber therebelow for burning fuel in suspension having side water walls including appropriate headers located outside the combustion chamber, upcomers for said water walls connected into the circulation of the boiler, said

upcomers being directed inwardly then longitudinally of the boiler, and being connected into a header of said boiler so as to constitute a portion of a row of the tubes thereof, and means for introducing fuel to be burned in said combustion chamber.

45 3. In combination with a substantially horizontal tubular boiler, a combustion chamber therebelow largely defined by tubular water walls including side tubular walls, and a rear tubular wall having appropriate headers and upcomer tubes for connecting said tubular walls into the circulation of the boiler, said upcomer tubes being arranged to constitute a row of the tubes of the boiler, and means for introducing fuel to be burned in said combustion chamber.

50 4. In combination with a substantially horizontal tubular boiler, a combustion chamber therebelow including side tubular walls, upper and lower headers into which the tubes thereof connect, a rear tubular wall, an upper header and lower junction boxes into which the tubes thereof connect, a water screen in the lower portion of the combustion chamber, a header at one end thereof into which the tubes of said screen connect, the other end of said tubes connecting into the lower junction boxes of the rear wall, a downcomer connection from the boiler to said water screen and to said side walls, and upcomer means leading from the side walls and the rear wall to the boiler comprising a plurality of tubes arranged to constitute a row of the tubes of the tubular boiler.

55 5. In combination with a tubular boiler, a combustion chamber therefor including side tubular water walls, tubes of which are shorter than other tubes thereof, a lower header for said tubes, an upper header for the shorter tubes, an upper header for the longer tubes, means establishing communication between said upper headers, and upcomer tubes for said side walls comprising a plurality of tubes arranged to constitute a row of the tubes of said boiler, said combustion chamber having a throat into which the longer tubes extend.

60 6. In combination with a tubular boiler, a combustion chamber therefor including side tubular water walls, tubes of which are shorter than other tubes thereof, a lower header for said tubes, an upper header for the shorter tubes, an upper header for the longer tubes, means establishing communication between said upper headers, and downcomer and upcomer means for connecting said walls into the circulation of the boiler, said combustion chamber having a throat into which the longer tubes extend.

65 In testimony whereof I have hereunto signed my name.

STANLEY A. JACQUES.
